UNITED STATES PATENT OFFICE

169,860

TEXTILE FABRIC

Edna May Molenaor, Rutherford, N. J., assignor to Everfast Fabrics, Inc., New York, N. Y.

Application November 14, 1952, Serial No. 22,279

Term of patent 7 years

(Cl. D92—1)

To all whom it may concern:

Be it known that I, Edna May Molenaor, a citizen of the United States of America, residing in Rutherford, county of Bergen, and State of New Jersey, have invented a new, original, and ornamental Design for a Textile Fabric, of which the following is a specification, reference being had to the accompanying drawing, forming part thereof, wherein,

The figure on the drawing is a plan view of a textile fabric showing my new design. The dot and dash lines on the drawing outline a design unit, which unit is repeated in regular succession as indicated by the extensions beyond the unit boundaries.

I claim:

The ornamental design for a textile fabric, substantially as shown and described.

EDNA MAY MOLENAOR.
